UNITED STATES PATENT OFFICE.

HARRY A. WARDY, OF ST. LOUIS, MISSOURI, ASSIGNOR TO WALTER M. BLINKS,
TRUSTEE, OF KALAMAZOO, MICHIGAN.

FILING-CABINET.

1,146,777.

Specification of Letters Patent. Patented July 13, 1915.

Application filed September 23, 1911. Serial No. 650,936.

To all whom it may concern:

Be it known that I, HARRY A. WARDY, a citizen of the United States, residing at the city of St. Louis, State of Missouri, have invented a new and useful Filing-Cabinet, of which the following is a specification.

This invention relates to filing cabinets and more particularly to filing cabinets of the usual alphabetical arrangement as well 10 as to cabinets arranged for the filing of correspondence, documents and other papers indexed by or according to date.

In handling business correspondence, and other matters of commercial routine, it is 15 convenient and often necessary to have certain matters brought to the attention of the correspondent at certain predetermined periods, and especially is this true in a business in which what is usually termed the "follow 20 up" system is employed. This periodical selection of certain matters requiring attention at predetermined dates has been accomplished usually by using, supplemental to the usual alphabetical index or file, an index 25 of calendarial arrangement; in some systems the alphabetical index is dispensed with and the correspondence and other papers are filed according to calendar classification alone.

It is apparent that a double classification 30 is useful and desirable and it is one of the chief objects of my present invention to provide a single filing cabinet or system arranged so that papers of all kinds may be 35 filed in any desired sequential order, and at the time of filing may be adjusted so that they will be withdrawn from the files according to another classification without disturbing the arrangement of the papers remaining 40 in the cabinet.

Another object of my invention is to equip a filing cabinet with suitable manipulative means for selecting, and, in the embodiment shown, for withdrawing from the cabinet 45 any desired or predetermined articles, papers and the like contained in the cabinet.

Other objects of the invention will readily appear from the following detailed description of my improvement, reference being 50 made to the accompanying drawings in which—

Figure 1 is a plan view of the cabinet, one of the sides thereof being lowered. Fig. 2 is a side view of the cabinet opened as shown

in Fig. 1. Fig. 3 is a portion of a transverse 55 section of the cabinet, showing in detail a part of the selecting device. Fig. 4 is a broken sectional plan view of a side of the cabinet, also showing in detail a portion of the selecting device. Fig. 5 is a transverse 60 section view of a portion of the cabinet showing one side thereof dropped and certain sheets or folders removed from the body of the cabinet. Fig. 6 is a front view of the cabinet in normal position, a portion thereof 65 being broken away showing the rear bearings for the shaft which constitutes a portion of the selecting device. Fig. 7 is a top view of one of the hooks which constitutes one of the elements of the selecting device, 70 and Fig. 8 is a front view showing one of the hooks to be applied to a sheet, or folder.

In the embodiment illustrated in the drawings I have shown one unit, that is one filing case, which case, as will be readily 75 understood, may be used singly or several units may be used together to form a filing cabinet of any desired capacity. By simple mechanical variation in details and dimensions receptacles adapted to the filing of any 80 letters, records, documents, and all papers or cards which ordinarily constitute the archives of any business or professional offices, may be provided.

I have illustrated my invention embodied 85 in a case comprising a bottom wall 1, end walls 2 secured to the bottom 1, two side walls 3, hinged at 4 to the bottom 1, and a removable top 5. In normal adjustment the sides are raised and the top fitted in place, 90 retaining the parts in the relation shown in Fig. 6. It is obvious that the receptacles may be made without a top, and that the sides may be retained in normal or closed position by a latch device or other suitable 95 means. Longitudinal strips 6 secured to the bottom 1 adjacent to the sides of the case constitute guides for the sheets or folders contained in the cabinet. The distance between the inner surfaces of the strips 6 is 100 the width of the sheets filed, and the edges of the sheets or folders are retained in longitudinal alignment thereby. A shaft 7, which is provided with a knob or handle 8, is arranged to be mounted in bearings arranged 105 in pairs, and thereby held in operative adjustment. A small rod 9, having its ends bent at right angles and attached to shaft 7,

- as shown in Fig. 4, constitutes a swinging bail, whereby hooks carried by the sheets or folders may be engaged, in the manner hereinafter more fully explained, when the shaft 7 is rotated. Bearing plates 11, having angular slots 10 therein, are secured to the side walls 2 adjacent to the rear of the case. As shown in Fig. 5 the lower portion of the slots 10 are adapted to receive and journal the rear end of the shaft 7. A series of holes 12 in the front bearing plates 11, register with the bearing portions of the slots 10, and are adapted to receive and journal the front end of the shaft 7. The side walls 3 are provided with inwardly extending flanges 13. The two flanges at the front end of the case are provided each with a series of holes 14, which holes register with the holes in the front bearing plates, and with the bearing portions of the slots 10, in the rear bearing plates 11, so that when the shaft 7 is mounted in its bearings the front end thereof extends through the flange 13 and receives the removable knob or handle 8. In the embodiment shown, the knob 8 is arranged with a key formed in the hub thereof, which is adapted to fit into a channel in the end of the shaft 7, thus forming a lock so that the shaft may be rotated by the manipulation of the knob.
- In mounting the shaft 7, the knob or handle 8 is removed, the shaft 7 passed through the registering set of holes in the front bearing plate and flange, and the opposite end of the shaft mounted in the bearing portion of one of the slots 10, which register with the holes in the front of the case. The knob or handle 8 is replaced, and the shaft 7 with the bail 9 inclined downwardly, is ready for manipulation as hereinafter explained.
- In Figs. 7 and 8 of the drawings I have illustrated in detail a preferred form of hook to be applied to the sheets or folders, which hook coöperates, as will be herein-after more fully explained, with the shaft 7 in selecting and withdrawing certain selected sheets or folders. The hook, as illustrated, is formed from a flat strip of spring metal, a part of the material of which is bent back on a line intermediate of its length, the outer ends thereof being slightly flared, as shown at 15 in Fig. 7, thus forming the body of the hook, which may be readily adjusted and held in position on a folder, card or other flat sheet. It will be observed that when placed upon a folder the body portion of the hook forms a clasp which serves to bind the leaves of the folder together. In Figs. 3 and 5 the manner of applying said hooks to a sheet or folder is clearly illustrated. The hook portion 16 is stamped out, and the sheet or folder is inserted between the two leaves forming the gripping portion of the hook, and any character on the

sheet or folder back of the opening in the front leaf will be exposed to view through the opening.

In my present embodiment, I arrange the folders or sheets with a series of numerals 70 from 1 to 16 beginning at the upper left hand corner of the card and numbering downwardly adjacent to the edge of the sheet. On the right hand side I complete the numerals beginning with 17 and including the numeral 31, thus representing the calendar days of the month. The holes 14 through the flange in the side pieces are numbered or lettered to correspond with the numbering or lettering on the sheets or folders. It is obvious that any other characters than numbers may be used, such for instance, as lettering, abbreviations for the months, or in short any system of indexing that may be desired.

From the foregoing it will be understood that the operation of my devices is as follows: The sheets or folders 17 are placed in the file and divided by guides indexed in any desired manner, such for instance, as in alphabetical order. At the time of filing, the gripping portion of a hook 16 is engaged on the edge of the sheet or folder at a point along its edge which corresponds to the date, lettering or other classification 85 by which it is to be selected and withdrawn. If the files are to be withdrawn in calendarial order, the shaft 7 is mounted in the bearings corresponding to a selected date. The bail 9 inclines downwardly in the space 100 between the sides of the case and the edges of the sheets or folders. The hooks on all sheets or folders to be withdrawn on such date are arranged in alinement with and extend into the space above the bail 9. In 105 selecting the files or sheets the shaft 7 is rotated so as to raise the bail 9 which causes it to engage with all of the hooks 16 that have been set for the selected date. The bail 9 is then further raised by rotation of the 110 shaft 7 thereby raising all the selected folders or sheets so as to clear the guide strip 6. The side of the case is now released, and allowed to open downwardly which operation draws out all the sheets or folders whose hooks have been engaged by the bail. The shaft 7 is now set for the next withdrawal, the side replaced in normal position and the selecting device ready for further operation.

Several changes in the details of construction will readily suggest themselves which would be within the limits of the spirit and scope of my invention. I do not limit myself, therefore, to exact details, but

What I claim and desire to secure by Letters Patent is—

1. In a filing system, a container, flat sheets arranged in said container, hooks adapted to engage said flat sheets, comprising a body portion composed of two clamp-

ing leaves, a hook portion stamped from one of said leaves projecting beyond the edge of said flat sheets, said leaves being adapted to receive and hold between their inner surfaces the sheets, and means for selectively engaging said hooks, substantially as specified.

2. A filing system comprising a case, flat sheets in said case, a guide for preserving the edges of said sheets in alinement, hooks adapted to be adjusted at different positions on said sheets, and a selecting device adapted to engage with said hooks and thereby select certain of said sheets in said case, substantially as specified.

3. In a filing cabinet, the combination with a folder arranged to receive papers between the leaves thereof, of a clasp arranged to bind the leaves of said folder together, a hook on said clasp extending beyond the edges of said folder, and adjustable means for engaging said hook whereby said folder may be moved, substantially as specified.

4. In a filing cabinet, a plurality of leaves, a hinged support, and means operable to connect said support with selected ones of said leaves so that movement of said support will also move said leaves, substantially as specified.

5. In a filing cabinet, a plurality of leaves, a hinged support, hooks on said leaves, and means on said support operable to engage said hooks so that movement of said support will also move said leaves, substantially as specified.

6. In a filing cabinet, a plurality of leaves, hooks on said leaves, a hinged support, a rod or shaft on said support, a bail on said rod or shaft, and means for engaging said bail with said hooks, substantially as specified.

7. In a filing system, the combination with a case having one member thereof hinged, a shaft mounted in bearings carried by said hinged member, a bail carried by said shaft, sheets in said case, elements arranged to be carried by said sheets, characters on one edge of said sheets by which the last named elements may be positioned for selective engagement by said bail, substantially as specified.

8. In a filing cabinet, the combination with a series of sheets arranged in the cabinet, and parts in connection with said sheet whereby said sheets may be moved, of a pivotally supported bail arranged to engage with said means when said bail is moved, and means for moving said bail.

9. In a filing cabinet arranged to contain folders or sheets, the combination with a hinged wall of said cabinet, of engaging members adapted to be adjusted at selected positions on said folders or sheets, and means operable to connect said wall and selected ones of said engaging members, so

that movement of said wall will move all of the sheets or folders whereon said selected engaging members are placed, substantially as specified.

10. A cabinet, sheets arranged in said cabinet in a predetermined order, engaging members adapted to be adjusted at different positions on said sheets, a hinged wall, a selecting device carried by said hinged wall, adapted to engage with said engaging members and thereby select certain of said sheets in said cabinet, when said wall is moved.

11. In a filing cabinet, a plurality of folders or sheets, a hinged wall, and means operable to connect said wall with selected ones of said sheets so that movement of said wall will move said selected sheets.

12. In a filing cabinet, a plurality of sheets arranged in said cabinet, hooks on said sheets, a movable support and means on said support operable effectively to engage said hooks so that movement of said support will move said sheets.

13. In a filing cabinet, a plurality of sheets, hooks on said sheets, a movable support, a shaft on said support, a bail on said shaft, and means for operating said shaft effectively to engage said bail with said hooks.

14. A filing system comprising a series of cards arranged in a predetermined order, adjustable engaging members adapted to be adjusted at different positions on said cards, a hinged wall, and a selecting device carried by said wall, adapted to engage with said engaging members and thereby select certain of said cards.

15. A filing system comprising a series of cards, adjustable hooks on said cards, and means operable effectively to engage selected ones of said hooks.

16. In a cabinet, the combination with a folder arranged to receive papers between the leaves thereof, of a clasp arranged to bind the leaves of said folder together, and a hook formed integral with said clasp, extending beyond the edge of the folder, of a device for engaging said clasp whereby said folder may be moved, substantially as specified.

17. In a filing cabinet, a plurality of folders arranged in a predetermined order, a pivoted support constituting a portion of the cabinet, engaging members arranged to be detachably positioned on an edge of said folders and to bind the leaves thereof together, and means on said support operable to engage said engaging members so that movement of said support will also move said folders, substantially as specified.

18. In a filing cabinet, the combination with a drawer having one wall thereof arranged to be moved, a support carried by said wall, a bail carried by said support, sheets arranged in said drawer, index char-

acters on said sheets, and elements arranged to be positioned on said sheets for selective engagement by said bail.

19. In a filing cabinet, the combination 5 with a receptacle, a series of filing elements arranged side by side within said receptacle, index characters near each vertical edge of said elements, and engaging members adapted to be located at different positions 10 on the vertical edges of said elements as determined by said index characters, of a device for engaging all of said engaging members corresponding to the same index characters on said filing elements, means for 15 supporting said device in different positions to engage selected ones of said members, and means for moving said device effectively to withdraw from said receptacle the filing elements to which are connected the engaging 20 members which are engaged by said device.

20. In a filing system, the combination with a receptacle, pivot connections for one wall of said receptacle, a device mounted on 25 said pivoted wall, sheets arranged in said receptacle, adjustable elements adapted to engage said sheets, and means for connecting the device carried by said pivoted member with said adjustable elements, substantially 30 as specified.

21. In a filing cabinet, the combination, with a series of filing elements within the cabinet, engaging devices on the side edges of said filing elements in different horizontal 35 planes, a pivoted support at the side of said cabinet, a device for selectively engaging said engaging devices, means for supporting said device in different positions on said pivoted support, and means for moving 40 said device to engage selected ones of said engaging devices, substantially as described.

22. In a filing cabinet, the combination with a series of filing elements within the 45 cabinet, engaging members on the side edges of said filing elements, a support pivoted at the side of said cabinet, a device for selectively engaging said engaging members, means for supporting said device in different 50 positions on said pivoted support, and means for rocking said device when in any one of said positions to engage correspond-

ing groups of said engaging members, substantially as described.

23. In a filing cabinet, the combination 55 with a series of filing elements within the cabinet, engaging members on the side edges of said filing elements, a support pivoted at one side of said cabinet, a bail pivotally carried by said support adjacent to the vertical side edges of said filing elements, and a manually operable device for moving said bail into engagement with said engaging members whereby the corresponding filing elements will be moved out of said cabinet 60 when said support is moved away from said cabinet.

24. In a filing cabinet, the combination with a series of filing elements within the cabinet, groups of engaging members on the 70 side edges of said filing elements, a support pivoted at the side of said cabinet, a device for selectively engaging said groups of engaging members, means for supporting said 75 device in different positions on said pivoted support, and means for rocking said device when in any one of said positions to engage all of said engaging members in the same group adjacent to said device.

25. In a filing cabinet, the combination 80 with a series of filing elements within the cabinet, adjustable engaging members on the side edges of said filing elements arranged in groups, a support pivoted at the side of said cabinet, a device for engaging 85 selected groups of said engaging members, means for supporting said device in different positions on said pivoted support to engage selected groups of said engaging members, and manual means for moving said device into and out of engagement with the adjacent group of engaging members, whereby said support and device may be moved outwardly to withdraw from the cabinet the filing elements whose members are engaged 90 with said device, at the will of the operator.

In witness whereof, I have signed this specification in the presence of two subscribing witnesses.

HARRY A. WARDY.
